Patented Apr. 18, 1916.

UNITED STATES PATENT OFFICE.

JOHN A. LANIGAN, JR., OF BROOKLYN, NEW YORK.

AUTOMATIC TRAIN-STOP.

1,180,158.

Specification of Letters Patent. Patented Apr. 18, 1916.

Application filed May 10, 1915. Serial No. 27,163.

To all whom it may concern:

Be it known that I, JOHN A. LANIGAN, Jr., a citizen of the United States, residing at Brooklyn, in the county of Kings, State of New York, have invented certain new and useful Improvements in Automatic Train- Stops; and I do hereby declare the following to be a full, clear, and exact description of the invention, such as will enable others skilled in the art to which it appertains to make and use the same.

This invention relates to new and useful improvements in automatic train stops, and is particularly directed to the provision of a device adapted to be positioned along a track, and preferably operated in connection with a conventional visual signal to actuate certain mechanism carried by the train for stopping the same.

It is generally the object of the present invention to improve the structure and efficiency of train stopping devices of this character, and to this latter end it is more particularly the object to provide such train carried mechanism, which when actuated by mechanism along the track will operate in a sufficiently slow manner to assure proper manipulation of the air valves or other stopping means utilized.

With the above and other objects and advantages in view, the invention resides more particularly in the novel combination, formation and arrangement of parts as more fully hereinafter described and pointed out in the appended claims.

Reference is had to the accompanying drawings wherein similar characters of reference designate corresponding parts throughout the several views, and in which: Figure 1 is a view in plan of the improved train stopping device. Fig. 2 is a longitudinal sectional view therethrough, and, Fig. 3 is a transverse sectional view taken on the line 3-3 of Fig. 1.

Referring now more particularly to the accompanying drawings, 5 designates a pair of tracks and 6 a suitable visual signal mechanism.

The improved device includes a relatively long permanent magnet 7, which is secured on a bar 8 extending longitudinally between the tracks and having its ends journaled in suitable bearing blocks 9. A wire 10 is secured to the bar, and a second wire 11 is also secured thereto and trained therearound

and extended with the wire 10, these wires being preferably connected to or otherwise operated by the wires actuating the visual signal, this being effected in any desired manner. Thus upon actuation of the visual signal the magnet will be moved to either lie in inoperative position or in operative raised position to engage a suitable armature member carried by the train. This armature member comprises an iron block 12 which is suitably held under the train in a detachable manner, as by the hook arm 13, so that when it passes over the magnet 7 in raised position it will be drawn from said arm and cling to the magnet. A shaft 14 is carried transversely by the train, and secured on the shaft is a spool 15 on which is wound a considerable length of wire 16 having one end secured to the armature. The shaft 14 also carries a worm gear 17 of relatively low pitch which meshes with a pinion 18 formed on a shaft 19 which is operatively connected in any desired manner to the air and throttle valve mechanisms of the train to actuate them to stop the same. By this construction, the wire 16 which is unwound from the spool at a comparatively great speed, rotates the shaft 14 at such high speed that it could not be directly connected to the train control mechanism, but by the provision of the low pitch worm gear, the motion is reduced to adapt it for actuating the said control mechanism.

In the operation of the device when the magnet 7 is swung on the rod 8 to a raised or operative position, a train passing thereover will have its armature 12 slip off the hook 13 and cling to the magnet, thus unwinding the wire on the spool and causing the shaft 14 to be rotated with a corresponding transmission of its motion to the train control mechanism as described. A simple means has thus been provided for reducing the motion imparted to parts of a moving train by means positioned along the track, whereby the train control mechanism may be automatically operated by means positioned along the track when the train is moving therewith at a relatively high speed.

What I claim is:

1. In a train control, the combination of a shaft, a second shaft, gear means connecting said shafts and adapted to rotate the second shaft at a lesser speed, a length of flexible material wound on the first shaft,

and means at the end of the cable engageable by a stop arranged on the track to unwind the cable.

2. In a train control, the combination of 5 a shaft, a worm gear on the shaft, a second shaft adapted to actuate the control mechanism of a train, a gear on said second shaft meshing with the worm gear, a length of flexible material wound on the first shaft, and means at the end of the cable engageable with a stop arranged on the track to unwind the cable.

3. In a train control, a magnet adapted 10 to be disposed along a track, an armature

adapted to be detachably carried by a train, 15 a shaft carried by the train, a flexible member secured to the armature and wound on the shaft, and means including a reducing train of gears for actuating the control mechanism of a train upon rotation of the 20 shaft.

In testimony whereof, I affix my signature, in the presence of two witnesses.

JOHN A. LANIGAN, Jr.

Witnesses:
